(57) **CLAIM**

The ornamental design for a knife handle, as shown and described.

DESCRIPTION

FIG. 1 is a top perspective view of a knife handle, showing my new design;

FIG. 2 is a left end plan view showing the blade end thereof;

FIG. 3 is a right end plan view showing the butt end thereof;

FIG. 4 is a top plan view thereof;

FIG. 5 is a bottom plan view thereof; and,

FIG. 6 is a right side elevational view, the left side elevational view being a mirror image thereof.
